[57] CLAIM

The ornamental design for a seat, as shown and described.

DESCRIPTION

FIG. 1 is a perspective view of a seat embodying my new design;

FIG. 2 is a plan view of the seat of FIG. 1;

FIG. 3 is a side elevation view of the seat of FIGS. 1 and 2;

FIG. 4 is a front elevation view of the seat of FIGS. 1 through 3;

FIG. 5 is a view similar to FIG. 1, showing a love seat embodiment of the seat of my new design;

FIG. 6 is a side elevation view of the seat of FIG. 5, similar to FIG. 3; and

FIG. 7 is a plan view of the seat of FIG. 5, similar to FIG. 2.
